(No Model.)

S. HOADLEY.

DRAFTING INSTRUMENT.

No. 397,500.

Patented Feb. 12, 1889.

UNITED STATES PATENT OFFICE.

SILVESTER HOADLEY, OF GOSPORT, INDIANA.

DRAFTING-INSTRUMENT.

SPECIFICATION forming part of Letters Patent No. 397,500, dated February 12, 1889.

Application filed August 28, 1888. Serial No. 284,000. (No model.)

To all whom it may concern:

Be it known that I, SILVESTER HOADLEY, a citizen of the United States, residing at Gosport, in the county of Owen and State of Indiana, have invented certain new and useful Improvements in Drafting-Instruments, of which the following is a specification.

The object of my said invention is to produce an improved construction of instrument, by which any desired distance may be divided into any given number of equal spaces. This object is accomplished by hinging or pivoting a graduated bar to a suitable frame-work at one end, and securing said bar at the other end to a curved arm forming a segment of a circle of which the hinge-joint is the center. The bar should have several sides, and each side should have a graduation different from the others. There should also be a thumb-nut to fasten it to any desired position, and a draftsman's square (either with or without the peculiar attachment to be hereinafter described) is to be used in operating the device.

Referring to the accompanying drawings, which are made a part hereof, and on which similar letters indicate similar parts, Figure 1 is a perspective view of my improved instrument; Fig. 2, a top or plan view of the same, two positions of the pivoted bar being shown, one by means of dotted lines; Fig. 3, a transverse sectional view looking toward the right from the dotted line 3 3 in Fig. 2; Fig. 4, a detail sectional view on the dotted line 4 4 in Fig. 2, and Fig. 5 a detail section through the square on the dotted line 5 5 in Fig. 2.

In said drawings the portions marked A represent the base of the instrument, B the pivoted bar, C the curved arm, and D the square.

The base A is generally a bar of wood made in the form of a ruler, and it preferably has upon its upper edge a scale (shown as fifteen inches long) by which measurements may be had. Two arms, A' and A², extend out therefrom, to one of which the bar B is hinged or pivoted, and from the other of which the curved arm C extends, or with which said curved arm is formed in piece. These arms A' and A² permit a space in which to work alongside the base A, between it and the bar B. The frame which the parts A, A', and A² form should be strong and substantial, so that

the instrument may give accurate results in use.

The bar B is secured to the arm A' of the frame by a hinge or pivot joint, b, and at the other end it is secured to the curved arm C. This bar is preferably made with several sides, (it is shown as having eight sides, or octagonal,) and each side is spaced equally throughout its length, the divisions being preferably shown by points, as indicated in the drawings. The graduations upon the several sides are different from each other, in order that the instrument may be adapted to a great variety of uses. In order that the bar B may easily rotate, the hinge by which it is secured to the standard A, and also the means of attachment to the curved arm C, must be so constructed as to permit said bar to revolve freely thereon. To this end the rod or shaft B' may extend entirely through the bar, and these attachments be made to said shaft, so that the bar itself shall be free to turn thereon. In order, however, that it shall not turn too easily, a spring, b', may be interposed between its end and the inner face of the curved arm C. That portion of the attachment which comes in immediate contact with the curved arm C is preferably formed with an opening or mortices, through which said arm passes, and a thumb-nut, b², is placed upon the outer end of said attachment, and by means of this nut when the bar is moved to the desired position it can be securely held there by turning said nut so it will bear against said arm, or a washer, c, placed between it and said nut.

The arm C is secured to the arm A² or to the end of the base A, (said arm A² being of no particular use, except to give the instrument a symmetrical appearance,) and extends out a sufficient distance, so that the bar B may be moved to any desired angle and there secured. Its only purpose is to enable said bar B to be held securely to the desired position.

The square D is, in its general form, substantially an ordinary draftsman's square. As it is, however, sometimes preferable that the markings made by its use shall be at something of an angle, as when it is desired in laying off lettering to make the letters italic in form, I have provided a wing, D', which extends down from the blade of the square to the

surface on which the instrument rests, which wing is mounted upon a pivot, d' . This pivot extends up through the blade of the square, and its upper end is preferably threaded and 5 bears a thumb-nut, d^2 . By this means said wing can be secured at any angle with the blade of the square desired, or directly in line therewith, as may be necessary to enable the work in hand to be properly executed. As will be 10 readily understood, this adds greatly to the convenience and expedition with which such work can be performed.

As before stated, the object of this invention is to enable the user to divide into equal 15 spaces any desired distance. This is useful in many sorts of drafting, particularly in such work as the dividing of the width of tombstones and monuments when laying out the lettering for the inscriptions thereon. For 20 illustration, suppose that the available space for any certain line of lettering is eleven inches and the number of letters to be put in the line will require twenty-seven spaces. In using 25 an instrument of the character herein shown I would first place the square D so that the side of its blade where it crossed the part A would register with the mark indicating eleven inches. I would then turn the bar B until a point indicating twenty-seven (or a 30 multiple thereof) was near the blade where it crossed the bar. I would then move said bar on the curved arm C until said point was brought exactly alongside said blade, fasten the bar B in that position, and then by slipping 35 the square from point to point and making a mark at each one (or each second or third one, as the case might be) the space would be exactly evenly divided into the twenty-seven spaces required. As the instrument I have made is constructed, it would be 40 more convenient to bring the bar so that the fifty-fourth point would come alongside the square when it crossed the bar A at the eleventh-inch mark, and then move the 45 square two points on the bar B for each mark made. In the practical laying out of letters where the letters are large the work may be much facilitated by so arranging the instru-

ment that each letter laid out will take, say, five spaces and a single space be the distance 50 between the letters, in which case the position of both sides of each letter and the proper distance between the letters are all accurately determined at one operation.

I do not by any means expect to limit myself to the above use of my invention, as it may advantageously be put to a variety of uses, but have described that use as among those to which it is peculiarly adapted and where it is of great value. 60

Having thus fully described my said invention, what I claim as new, and desire to secure by Letters Patent, is—

1. In a drafting-instrument, the combination of the base A, provided with the arms A' 65 and A², the bar B, hinged to said arm A', the curved arm C, extending out from said arm A², said bar B being mounted to slide thereon, and the draftsman's square D, all arranged and operating substantially as set 70 forth.

2. The combination, in a drafting-instrument, of a base or frame, a curved arm extending out therefrom, and a graduated bar having graduations of different lengths upon 75 several sides hinged to said base or frame and revoluble upon its own axis, whereby either of its sides may be brought into use, substantially as set forth.

3. The combination, in a drafting-instrument, with the main structure thereof, of a draftsman's square extending across it, the blade of which is provided with a wing extending down to the surface on which the instrument rests, said wing being pivoted as 85 described, whereby the markings can be made at an angle with the direction in which the square is moved over the instrument, substantially as set forth.

In witness whereof I have hereunto set my 90 hand and seal, at Indianapolis, Indiana, this 23d day of August, A. D. 1888.

SILVESTER HOADLEY. [L. S.]
Witnesses:
